UNITED STATES PATENT OFFICE.

ALEXANDER S. ROWLAND, OF NEW YORK, N. Y.

DESIGN FOR A CANDLESTICK.

Application filed May 10, 1923. Serial No. 6,126. Term of patent 7 years.

To all whom it may concern:

Be it known that I, ALEXANDER S. ROWLAND, a citizen of the United States of America, residing at New York, in the county and State of New York, have invented a new, original, and ornamental Design for a Candlestick, of which the following is a specification, reference being had to the accompanying drawing, forming part thereof.

The drawing is a perspective view of the candlestick.

I claim:

The ornamental design for a candlestick, as shown.

ALEXANDER S. ROWLAND.
